UNITED STATES PATENT OFFICE.

ARTHUR E. PELLERIN, OF STANDISH, NEW YORK.

SUSPENDERS.

Application filed July 30, 1926. Serial No. 126,045.

The present invention relates to improvements in suspenders and has for its principal object to provide a suspender construction which will readily adapt itself to the 5 movement of the wearer's body.

Another important object of the invention is to provide a pair of suspenders which includes a means for a drawers supporting attachment which can be readily attached to or 10 detached from the trouser suspenders without disconnecting or adjusting the latter in any way.

A further object of the invention is to provide a pair of suspenders wherein the same 15 includes a means to permit the suspenders to be worn on the outside or on the inside of an outer or dress shirt.

A further object of the invention is to provide a pair of suspenders which is simple in construction, inexpensive, strong and durable, and further well adapted to the purpose for which it is designed.

Other objects and advantages of the invention will become apparent from the following 25 description taken in connection with the accompanying drawings.

In the accompanying drawings forming a part of this application and in which like numerals designate like parts throughout the 30 several views:

Figure 1 is a rear elevation of the suspenders embodying my invention showing the same in use.

Figure 2 is an enlarged elevational view 35 of the connection between the free ends of each of the shoulder straps, there being shown in this figure the drawers supporting attachment as well as the means whereby the suspenders for the trousers may be attached 40 on the inside of an outer or dress shirt.

Figure 3 is an enlarged sectional view taken approximately on line 3-3 of Figure 2.

Figure 4 is an enlarged detail elevation of 45 the fastener employed when the suspenders are to be worn on the inside of an outer or dress shirt, and

Figure 5 is a detail view showing the manner in which the suspenders support the 50 trousers and the drawers.

In the drawing wherein for the purpose of illustration is shown the preferred embodiment of my invention the numerals 1 and 2 designate a pair of shoulder straps which are adapted to extend over the shoulders of the wearer in the manner as clearly

shown in Figure 1. A transversely extending connecting strap 3 is secured at its respective ends to the straps 1 and 2, preferably to the portions of said straps which extend along the back of the wearer, and this is clearly shown in Figure 1. The shoulder straps as well as the transversely connecting back straps are provided with suitable adjusting buckles in the manner well known in 60 the art.

The ends of each of the shoulder straps are looped through the slots 4 formed in the loop plates 5. These loop plates 5 are provided with central lateral extensions 6 which 70 are embraced on either side by the arms of the tubular cord guides or loops 7 which are journaled thereon by means of the tubular rivets 8. The purpose of these tubular cord guides or loops 7 will be hereinafter more 75 fully described.

A relatively short vertically disposed connecting strap 9 is associated with the free ends of each of the shoulder straps 1 and 2 respectively, and the manner in which these straps 9 are connected to the free ends of each of the shoulder straps will be presently apparent. A loop plate 10 similar to the aforementioned plates 5 is provided with the slot 11 to accommodate the upper end 80 portion of the strap 9, the free upper end of said strap after extending through the slot 11 being stitched to the main body of the strap as at 12 with reference more particular to Figure 3.

Each of the loop plates 10 is provided with the central lateral extension 13 which is embraced on either side by the arms of the tubular guides 14. This tubular cord guide 14 is journaled on the central extension 13 by 90 means of the tubular rivets 15. Additional lateral extensions 16 are formed at the ends of the loop plates 10 and attached to each of the end extensions is the tubular cord guides or loops 17. The end cord guides or loops 100 are attached to the lateral extensions at the ends of each of the loop plates 10 by means of the tubular rivets 18.

A loop plate 19 is attached to the lower end of each of the connecting straps 9 and is also provided with a central lateral extension 20 to which is connected the tubular cord guide or loop 21 in the same manner as the aforementioned guides or loops are connected to the lateral extensions on the loop plates also 110 heretofore more fully described.

A running cord 22 extends through the

cord guides or loops 7 which are carried by the free ends of each of the shoulder straps and this cord passes through the guide or loop 14, the free ends of the cord extending 5 downwardly through the guides 17 along the sides of the connecting straps 9 and then through the lower cord guide 21 as is clearly shown in Figure 2.

A pair of trouser supporting loops 23 are 10 formed in each of the running cords 22 and these loops are adapted for engagement with buttons secured to the waist portion of a pair of trousers in the manner as clearly shown at 24 in Figure 1.

15 The running cord 22 will dispose the free ends of each of the shoulder straps in converging relation so that the ends of each shoulder strap will be disposed directly at the side of the body below the shoulder as is 20 shown in Figure 1, the loops 23 being attached to the trousers at the front and back of the waist portion adjacent the sides. The several guides or loops which are associated with the loop plates will permit the suspenders to readily adapt themselves to the movements of the wearer's body, thus preventing 25 any discomfort to the wearer.

The drawers supporting attachment which is adapted to be associated with the pair of 30 suspenders comprises a loop plate 25, the same being provided with the slot 26 and through which slot the upper end portion of each connecting strap 9 extends in the manner as clearly shown in Figure 3. A central 35 lateral extension 27 is formed on each of the loop plates 25 and carried by each of said extensions is the button 28. The drawers supporting attachment further includes the running cord 29, the free ends of which are 40 provided with the loops 30 for engagement with suitable buttons 31 attached to the waist portion of the drawers in the manner as clearly shown in Figure 5. The intermediate portion of each of the running cords 29 45 passes through the tubular cord guide or loop 32 which forms a part of the loop 33 which is adapted for detachable engagement with the button 28 in the manner well known in the art.

50 The provision of a drawers supporting attachment of the above mentioned character enables the same to be readily attached to or detached from the trousers supporting means without necessitating any material changes 55 of the suspenders.

For the purpose of permitting the suspenders to be worn on the inside of an outer or dress shirt so that the suspenders are rendered invisible, I provide the connecting means designated generally by the numeral 34 and shown more specifically in Figure 4. This connecting means comprises a pair of complementary members 35 and 36 respectively, each of which is formed of a single

strand of resilient wire and the adjacent ends 65 thereof are pivotally connected together as at 37. The outer end of each of the wire members is restricted to provide a clamping portion 38.

In use, four of such members are provided, 70 one pair for each of the shoulder straps as is shown in Figure 2. The restricted portion 38 of the upper loop 35 engages around the running cord 22 so that the members 34 will be carried by the running cord 22 and the 75 restricted portion 38 of the lower complementary members 36 are adapted to clamp a portion of the drawers and shirt so that the trousers may be supported properly, it being understood of course that the clamping 80 restricted portions of the lowermost loop members will engage the trousers from the inner side. In this manner the suspenders will not be visible and will therefore not present an unsightly appearance. 85

It will thus be seen from the foregoing description that I have provided a pair of suspenders which may be readily and easily attached to the trousers for properly supporting the same and furthermore by constructing a pair of suspenders in the manner as shown and described, the same will permit the wearer to move his body freely without any discomfort. 90

While I have shown the preferred embodiment of my invention it is to be understood that minor changes may be made therein without departing from the spirit of the invention and the scope of the appended 95 claim. 100

Having thus described the invention, what I claim as new and desire to secure by Letters Patent is:—

In a pair of suspenders, the combination with a pair of shoulder straps, the back portions thereof being connected, a connecting strap for the free ends of each of said shoulder straps, trouser supporting means associated with the free ends of each of the shoulder straps and the respective connecting straps, said means comprising a running cord, trousers connecting means associated with the free ends of the cord, said connecting means comprising a pair of complementary members formed of wire, the adjacent ends thereof being pivotally connected together, the outer end of each of the wire members being restricted to provide a clamping portion, one of said clamping portions engaging the free end portion of each cord, the other clamping portion adapted to clamp the trousers, and guide means for the supporting cord carried by the free ends of each of the shoulder straps and the respective connecting straps. 115 120 125

In testimony whereof I affix my signature.

ARTHUR E. PELLERIN.
